UNITED STATES PATENT OFFICE.

HARRY N. MILLER, OF CHICAGO, ILLINOIS, ASSIGNOR TO FANSTEEL PRODUCTS COMPANY, INC., OF NORTH CHICAGO, ILLINOIS, A CORPORATION OF NEW YORK.

ELECTROLYTIC CONDENSER.

Application filed April 9, 1927. Serial No. 182,302.

This invention relates to an electrolytic condenser of the type described in my co-pending application, Serial No. 173,031, filed March 5, 1927. It relates, more particularly, 5 to a unit comprising condenser cells, each of which is composed of filmed plates and conductive plates separated by insulating rivets and immersed in an electrolyte gel prepared by incorporating an electrolyte in a solution 10 of gelatin in glycerin.

The object of my invention is to provide an improved electrolytic condenser.

Other objects will be apparent from the detailed description.

15 In the accompanying drawings which represent a preferred embodiment of my invention,

Fig. 1 is a vertical section of my improved condenser, taken on lines 1—1 of Figs. 2 20 and 3.

Fig. 2 is a vertical section on lines 2—2 of Figs. 1 and 3.

Fig. 3 is a horizontal section taken on line 3 of Figs. 1 and 2.

25 Fig. 4 is a plan of the conductive plate showing the arrangement of the insulating rivets.

Fig. 5 is a horizontal section of said plate on lines 5—5 of Fig. 4.

30 Fig. 6 is a plan of the aluminum plate.

Fig. 7 shows the individual-cell container, and

Fig. 8 is a perspective view of the finished 35 condenser.

In the several figures, similar parts are referred to by like reference characters.

In various filter circuits, such as are used for eliminating the pulsations in rectified alternating current, a number of condensers 40 of high capacity are required. Electrolytic condensers have proven very satisfactory in that a large capacity may be obtained in a smaller volume than with the corresponding dry condensers. However, the electrolyte, in 45 the fluid state, has been objectionable, due to its corrosive effect and due to the inconvenience in handling it. By incorporating the electrolyte in a gel, I have found that the high capacity can be obtained without these 50 objectionable features.

The specific example described here is designed to be used with direct pulsating current. When a voltage is impressed on the 55 filmed aluminum plate, the cell acts as a condenser but when the voltage decreases, the

discharge of this condenser is in the form of a smooth curve and not an oscillating wave because the cell does not function as a condenser when a voltage is impressed on the negative plate.

60 A receptacle 1, preferably of stamped sheet metal, is provided with a series of apertures in one side, as shown in Fig. 8. A number of containers 11, 12, 13 and 14 are placed in the receptacle, as shown in Figs. 2 and 3. 65 Each of these containers is composed of insulating material, such as hard rubber, cardboard or the like, and if a fibrous material, such as cardboard, is used the container is impregnated with a waterproof material, 70 such as paraffin.

The condenser plates are preferably aluminum and iron, although any suitable valve metal may be used instead of aluminum, and any conductor or conductive metal may take 75 the place of iron. The preferred shapes of the sheets or plates are shown in Figs. 4 to 6.

Fig. 4 shows an iron plate provided with a tab 15 and with five holes 17 arranged as shown in the drawing. Into each of these 80 holes is fixed an insulating rivet 18, the ends of which protrude from the plate about $\frac{1}{2}$ to $\frac{1}{8}$ of an inch. The aluminum plates preferably have the tab 16 at the edge instead of in the center. The aluminum plates are 85 filmed in a saturated solution of sodium bicarbonate with a direct current potential of about 250 volts and, when dried, are alternately arranged with the iron plates in the container 11.

90 An electrolyte 19 is prepared by heating 1 part of gelatin with 5 or 6 parts of glycerin on a water bath until the gelatin is dissolved, saturating this solution with sodium bicarbonate and adding a small amount of lithium 95 hydroxide. This electrolyte is then poured between and around plates 13' and 14' in the container.

Cells 11 and 12 are shown with two plates, one of aluminum and one of iron. Cells 13 100 and 14 are shown as including four plates, two of aluminum and two of iron. It is understood, of course, that various numbers of cells and various numbers of plates per cell may be used, as the requirements of any particular use may demand.

Suitable wiring connections are shown in Figs. 2 and 3. All of the iron plates are connected by conductors 20 which are, in turn, connected to a lead out wire 21. A wire 110

- 22 is connected to the tab 16 of the aluminum plate in cell 11 and this wire is led out from one of the openings 25', as shown in Fig. 8. In a like manner the aluminum plate of cell 5 12 is connected to lead out wire 22'. The aluminum plates of cell 13 are connected to lead out wire 23 and the aluminum plates of cell 14 are connected to lead out wire 23'. Since the iron plates are wired in the center 10 and the aluminum plates are wired at the edge, there will be no likelihood of error in wiring the unit.

In practise, I employ wire with different colored insulation to correspond to the respective capacity of the condenser to which it is connected. For example, a green wire 15 may indicate connection to a two-plate condenser, red insulation to a four-plate condenser, white insulation to a six-plate condenser, etc., the negative lead of each condenser being represented by black insulation on the wire 21.

Since a common lead out wire is used for all condenser cells in the unit, it is important that the containers of each cell be good 25 insulators and that they be waterproof for reasons which are deemed obvious.

When the units are in place and the wires are connected as above described, molten 30 paraffin 24 is poured over the cells, a strip of paper 25 is placed over the paraffin and a wax seal 26 is applied. If the wax seal is poured directly onto the paraffin the finish is not as satisfactory because some of the paraffin 35 melts and comes to the surface of the wax.

It will be seen that I have provided a compact unit comprising a series of electrolytic condensers that will find wide application in filter circuits. The electrolyte is in a non- 40 fluid state under normal operating conditions but, should the cell become heated, no damage will result because the insulating rivets will keep the plates from short circuiting. Should the voltage be accidentally 45 raised to too high a point and the film become punctured, the electrolyte will reform the

film. Since no appreciable current flows there will be no gassing. The tacky quality of the gel assures constant adhesion to the surfaces of the plates. 50

A condenser unit of the type described is especially adaptable for use in battery eliminators used in radio receiving sets.

While I have described in detail a specific example of my invention, it is understood 55 that I am not limited to the details shown except as defined by the following claims.

I claim:

1. An electrolytic condenser comprising a waterproof container, a filmed aluminum 60 plate, an iron plate, insulating means for keeping the plates in intimately spaced relation under all operating conditions, and an electrolyte comprising sodium bicarbonate, in a dry gelatin-glycerin gel. 65

2. An electrolytic unit comprising a plurality of receptacles, each including a filmed electrode and a non-filmed electrode, a lead for electrically connecting the non-filmed electrodes together, separate leads to the 70 filmed electrodes in the separate receptacles, and an ionogen incorporated in a dry glycerin composition in each of the receptacles.

3. A condenser unit comprising a plurality of filmed electrodes, separate receptacles adapted to contain said electrodes, a substantially dry electrolyte in each receptacle, a common conductor leading to the electrolyte in the several receptacles and individual conductors leading to the several 75 80 filmed electrodes.

4. In a water-proof electrolytic condenser a filmed aluminum electrode, a conductive electrode, insulating means for keeping the electrodes in intimately spaced relation under 85 all operating conditions, and an electrolyte comprising a substantially dry solution of an ionogen in glycerin.

In witness whereof, I hereunto subscribe my name this 6 day of April, 1927.

HARRY N. MILLER.
